(No Model.)

W. R. PRIME.

NURSING BOTTLE.

No. 323,597.

Patented Aug. 4, 1885.

UNITED STATES PATENT OFFICE.

WILLIAM REID PRIME, OF RICHFORD, VERMONT, ASSIGNOR OF ONE-HALF
TO SAMUEL BAXTER FOSTER, OF CHICAGO, ILLINOIS.

NURSING-BOTTLE.

SPECIFICATION forming part of Letters Patent No. 323,597, dated August 4, 1885.

Application filed October 25, 1884. (No model.)

To all whom it may concern:

Be it known that I, WILLIAM R. PRIME, a citizen of the United States, residing at Richford, in the county of Franklin and State of Vermont, have invented certain new and useful Improvements in Nursing-Bottles, of which the following is a specification, to wit:

This invention relates to an improvement in nursing-bottles; and it consists in certain peculiarities of the construction and arrangement of the same, substantially as will be hereinafter more fully set forth and claimed.

In order to enable others skilled in the art to which my invention appertains to make and use the same, I will now proceed to describe its construction and operation, referring to the accompanying drawings, in which—

Figure 1 is a side elevation, and Fig. 2 a central vertical section, of my improved bottle; and Figs. 3 and 4 are details of the same.

A represents a nursery-bottle, of glass or any other suitable material. This bottle is formed in two parts, divided transversely at or near its center, and the upper portion formed with shoulder *a* near its lower edge, from which the surface is tapered slightly, as at *a'*, while the adjacent edge of the lower portion is formed with an interior tapered end, *b*, into which the upper portion fits, and both contacting surfaces are ground to form a tight joint when closed. The outer surface of the lower portion of the bottle is formed with a screw-thread, and the joint is surrounded by a ring, *B*, also threaded, and provided with a flange, *b'*, to engage the shoulder *a*. When the two parts of the bottle are placed together and the ring screwed up, the joint is drawn firmly together and held water-tight, as indicated in the drawings. The upper part of the bottle is formed or provided with a hollow central stem or neck, *C*, running down through the interior to or past the joint between the two parts, and which is open at both ends, and at its upper end or base this neck or tube is upon the inside formed with two small notches, *c c*, the purpose of which will be presently explained.

The rubber tube *D* is of the usual form, and has the ordinary nipple, *D'*, secured to its outer end. Upon this tube is a collar, *D''*, having its

lower end split to form four prongs, *d d' d' d'*, the former of which have their ends or points turned out, and, when the tube is inserted into the neck or tube *C*, are sprung into the notches *c c* to retain it in place. The two latter prongs, *d'*, have their ends turned in against the rubber tube, and over the collar *D''* is screwed a ring, *D''*, which, on being screwed down, forces these prongs in upon the tube, thus compressing it, and enabling the flow of milk to be accurately and positively controlled.

In use the lower portion of the bottle is filled wholly or partially with milk, and the parts then secured together, as already explained. The rubber tube *D* is then inserted through the neck of the bottle till it enters the milk, and secured in place by the points *d*, while the others are compressed upon the tube to control the flow of milk. It will thus be seen that the bottle is readily taken apart for thorough cleansing, is secured perfectly tight when joined together, and, should the bottle be upset, the contents fall into the upper half, and its interior neck or tube being longer than the section, no liquid can leak out in such a position.

To prevent souring of the milk and supply a constantly-changing current of air to the milk, as well as to carry off the noxious air and gases arising therefrom and from the breath of the infant, is absolutely necessary to preserve the health of the user, and this is accomplished by the open neck *C*. The rubber tube *D* does not fill this neck, and space is left around it through which the air passes in and out. This accomplishes the object perfectly, and keeps the liquid sweet and pure at all times. While I prefer to use glass in the construction of this bottle, I do not desire to confine myself to this material, but wish to use any other material found suitable to the purpose.

The lower portion of the bottle is marked or provided in any way desired with a series of graduates, *m*, which serve as a guide in mixing given quantities of different liquids used in combination for nourishment. These also enable the nourishment to be given the infant in any desired quantities, which are positively

gaged, as will be seen at once. This is frequently of advantage in infants of delicate constitution.

Having thus fully described my invention, 5 what I claim as new, and desire to secure by Letters Patent, is—

1. A nursing-bottle formed in two parts, one of which is provided with a neck or tube extending inward, through which the exit-tube 10 is passed loosely, substantially as and for the purpose set forth.

2. A nursing-bottle having an inwardly-extending neck provided with small notches within its outer end, in combination with 15 a collar upon the flexible outlet-pipe, provided with prongs which are sprung into said notches to hold the tube in position without closing the neck of the bottle, substantially as and for the purpose set forth.

20 3. The combination, with the tube of a nursing-bottle, of a small collar placed thereon, and provided with two inwardly-turned prongs or points, and a ring screwed upon the

collar to compress these points, substantially as and for the purpose set forth.

4. A nursing-bottle formed in two parts, having their adjacent ends fitting one within the other, and formed with a ground joint drawn tightly together by a collar or band 30 screwed over it, and an open neck or tube extending inward from one of the parts of the bottle, in combination with a rubber tube passed loosely through this neck, a metal collar upon said tube, formed with two prongs 35 extending outward to engage notches in the base of the bottle-neck and two prongs turned inward upon the tube, and a screw-collar upon the tube to compress the latter prongs and regulate the flow of milk, substantially as and for the purpose set forth.

In testimony whereof I affix my signature in presence of two witnesses.

WILLIAM REID PRIME.
